52,118.

Specification for Design. **Patented June 18, 1918.**

Application filed October 28, 1917. Serial No. 198,733. Term of patent 7 years.

To all whom it may concern:

Be it known that I, MARY LA FETRA RUSSELL, a citizen of the United States of America, and a resident of the borough of Manhattan, city and State of New York, have invented a new, original, and ornamental Design for an Article of Manufacture, of which the following is a specification, reference being had to the accompanying drawing, showing a front view of a doll embodying my design.

While I have shown my design as embodied by way of example in a doll, I want

it to be understood that the application of the design is not limited to dolls, as it may obviously be embodied in various other articles of manufacture, such as cut-out dolls, cut-out dinner cards, bean-bags, and paper-weights. It is to be understood that my claim includes all substantial equivalents of my design as shown and described.

I claim:

The ornamental design for an article of manufacture substantially as shown and described.

MARY LA FETRA RUSSELL.
